[57] CLAIM

The ornamental design for a telephone booth, as shown and described.

DESCRIPTION

FIG. 1 is a front perspective view of a telephone booth showing my new design;

FIG. 2 is a left side elevational view thereof, the right side view being a mirror copy of this view;

FIG. 3 is a front elevational view thereof;

FIG. 4 is a top plan view thereof;

FIG. 5 is a perspective view of a second embodiment of a telephone booth, the top being the substantially the same as the top of a telephone booth shown in FIGS. 1 to 4 of the drawings; and,

FIG. 6 is a rear elevational view of a telephone booth shown in FIGS. 1 to 4 of the drawings.
